INVENTOR

JOSEPH STUART.

UNITED STATES PATENT OFFICE.

JOSEPH STUART, OF ALLEGHENY, PENNSYLVANIA.

GEARING.

No. 877,678.

Specification of Letters Patent.

Patented Jan. 28, 1908.

Application filed April 13, 1907. Serial No. 367,927.

To all whom it may concern:

Be it known that I, JOSEPH STUART, a citizen of the United States of America, residing at Allegheny, in the county of Allegheny and State of Pennsylvania, have invented certain new and useful Improvements in Gearing, of which the following is a specification, reference being had therein to the accompanying drawing.

10 This invention relates to gearing, and the invention relates more particularly to that type of machine wherein a receptacle is mounted for oscillation to cause the clothes contained within the receptacle to be agitated by the water and cleansed thereby and by such detergent as may be placed therein.

15 The object of this invention is to provide a novel device adapted to be operated by a water motor for oscillating a washing machine, the device being compact, simple, strong and durable, and of such a construction as to insure a positive and easy oscillation thereof.

20 25 The present invention is an improvement upon my invention disclosed in an application for patent filed December 4th, 1906, Ser. No. 346,202, the present invention being wholly generic to the above mentioned case.

30 35 The preferred embodiments of my invention are illustrated and described in the present application, but I desire it to be understood that such changes in the structural details thereof as fall within the scope of the appended claims, can be resorted to without departing from the scope of the invention.

Referring to the drawing, forming part of this specification, wherein like numerals of reference designate corresponding parts throughout the several views, Figure 1 is a side elevation of my improved device as applied to a washing machine, Fig. 2 is a rear elevation of the same partly in section, Fig. 3 is a bottom plan of the device detached from the washing machine, Fig. 4 is an end view of the portion of the device shown in Fig. 3, Fig. 5 is a detail view enlarged, of a portion of the device, in section on the line 5—5 of Fig. 3.

40 45 50 In the accompanying drawing, I have illustrated a suitable support 1 for a tub or clothes receptacle 2, said receptacle being revolvably mounted upon the support 1, and provided with a handle 3, whereby said recep-

tacle can be oscillated manually if desired. 55 In connection with the support 1, I use a suitable bracket 4 for supporting a conventional form of water motor 5, said motor designed to reciprocate a rack 6 employed for operating my improved device as here- 60 after described.

The improved rack device consists of a skeleton segment shaped frame 7, suspended from the bottom of the tub 2 by brackets 8 forming part of the frame 7. The inner side 65 of the frame is provided with a segment shaped rack 9, while the outer side of the frame is formed with a segment shaped slot 10, the slot lying in a plane above the rack 9.

Suitably journaled upon the bracket 4 is a 70 pinion 11 adapted to mesh with the rack 6. The shaft 12 of the pinion 11 extends upwardly into the slot 10 of the frame 7, and directly above the pinion 11 the frame 7 is 75 provided with a sector 14 having teeth 15 upon its curved edge, said teeth meshing with the segment-shaped rack 9.

When the rack is reciprocated by the motor device 5, a corresponding movement will be 80 imparted to the pinion 11, which through the medium of the sector 14 and the rack 9 imparts an oscillatory movement to the tub 2, the frame 7 and the tub 2 being guided and limited in their movements by the fact of the shaft 12 protruding into the slot 10 of said 85 frame.

The support 1 is connected by coiled springs 16 with the bottom of the tub 2, said springs assisting in the oscillation of the tub and absorbing the jars and concussions, and 90 materially assisting in the action of the tub.

In employing my improved operating device in connection with a motor driven rack, I am enabled to oscillate any receptacle mounted for such purpose and equipped 95 with my improved device, therefore I do not care to confine my invention particularly as an attachment for washing machines of the type above described.

What I claim and desire to secure by Letters Patent, is:—

1. In a device of the class described, a frame adapted to be connected to a receptacle and formed with a segmental gear rack and a segmental slot spaced apart and concentric to the oscillating point of the receptacle, a stub shaft extending through said slot, a sector carried by said shaft and pro-

vided with a gear segment engaging the segmental gear rack of said frame, a gear wheel carried by said shaft, a reciprocating gear rack engaging said gear wheel, and means for operating said reciprocating gear rack.

2. In a device of the class described, a supporting base having a central pivot, a frame adapted to be connected to a receptacle and provided with a segmental gear rack and a segmental slot spaced apart and concentric to said pivot, a stub shaft carried by said base and extending through said slot, a sector carried by said shaft and having a gear segment engaging said segmental frame rack, a gear wheel carried by said shaft, a reciprocating rack engaging said gear wheel, and means for actuating said reciprocating rack.

3. A device for operating washing machines, consisting of a frame adapted to be connected to a machine, a segment-shaped rack carried by one edge of said frame, the opposite edge of said frame having a segment-shaped slot formed therein, a pinion mounted for oscillation adjacent to said frame, a toothed sector carried by said pinion and meshing with said rack, and means carried by said pinion and associated with said slot for guiding the movement of said frame.

In testimony wherof I affix my signature in the presence of two witnesses.

JOSEPH STUART.
